US00D712052S

(12) **United States Design Patent**
Thomas et al.

(10) **Patent No.:** US D712,052 S
(45) **Date of Patent:** ** Aug. 26, 2014

(54) **PORTABLE TENS DEVICE**

- (71) Applicant: **Modular Therapeutx, LLC**, Soddy Daisy, TN (US)
- (72) Inventors: **Charles M. Thomas**, Hixson, TN (US); **D. Keith Hagy**, Chattanooga, TN (US); **Donald Kay Riker**, Soddy Daisy, TN (US); **Nathan Anderson Pollock**, Suffolk Park (AU); **Brad Peter Ryan**, Graceville (AU); **Lee Anthony Rodezno**, Rowville (AU); **Troy Christiana Nyssen**, Flemington (AU)
- (73) Assignee: **Modular Therapeutx, LLC**, Soddy Daisy, TN (US)
- (**) Term: **14 Years**
- (21) Appl. No.: **29/484,480**
- (22) Filed: **Mar. 10, 2014**

Related U.S. Application Data

- (62) Division of application No. 29/395,407, filed on Jan. 13, 2012, now Pat. No. Des. 704,848.
- (51) **LOC (10) Cl.** 24-01
- (52) **U.S. Cl.** USPC D24/200
- (58) **Field of Classification Search**
USPC D24/169, 186, 200, 209–210; D10/78, D10/81; D13/168; 340/12.22; 607/48
See application file for complete search history.

(57) **CLAIM**

The ornamental design for a portable tens device, as shown and described.

DESCRIPTION

FIG. 1 is a top perspective view of the portable tens device of our new design.

FIG. 2 is a bottom perspective view of the portable tens device of our new design.

FIG. 3 is a front view of the portable tens device of our new design.

FIG. 4 is a rear view of the portable tens device of our new design.

FIG. 5 is a right side view of the portable tens device of our new design.

FIG. 6 is a left side view of the portable tens device of our new design.

FIG. 7 is a top view of the portable tens device of our new design; and,

FIG. 8 is a bottom view of the portable tens device of our new design.

1 Claim, 8 Drawing Sheets
